(57) **CLAIM**

I claim the ornamental design for a coin changer, as shown and described.

DESCRIPTION

FIG. 1 is a top front perspective view of a coin changer showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top rear perspective view thereof.

The broken line portion of the figure drawings is included to show portions of the article that forms no part of the claimed design.

1 Claim, 8 Drawing Sheets
